UNITED STATES PATENT OFFICE.

WILLIAM H. CLAUSEN, OF MELROSE, MASSACHUSETTS.

GAME APPARATUS.

Application filed January 31, 1922. Serial No. 532,997.

To all whom it may concern:

Be it known that I, WILLIAM H. CLAUSEN, of Melrose, in the county of Middlesex and State of Massachusetts, a citizen of the 5 United States, have invented a new and useful Improvement in Game Apparatus, of which the following is a specification.

My invention relates to apparatus for a parlor game comprising a board or table 10 of peculiar construction representing a field and a number of elements which may be placed and moved according to the rules of the game to be played, representing, for example, goal posts and men and one or 15 more sliding members representing balls or the like which may be knocked about on the table by a stick representing, for example, a hockey stick, the number of elements depending upon the game to be played.

20 My invention will be understood by reference to the drawings in which it is shown in its preferred form.

Figure 1 is a plan of a board showing the elements arranged for beginning a game of 25 hockey to be played according to certain rules to be suggested hereinafter.

Fig. 2 is a section on line 2—2 of Fig. 1.

Fig. 3 shows in perspective one of the 30 elements representing the players or men.

Fig. 4 is a similar view of one of the goal posts.

Fig. 5 is a perspective view of a "puck", and

Fig. 6 is a similar view of the stick by 35 which the puck is propelled.

The board may be made of wood and say 18 inches by 24 inches surrounded by a moulding *a* of sufficient height to prevent the puck from sliding off the board. The 40 board has preferably a large number of holes *a*¹ in it scattered throughout the field represented by the said board and preferably in staggered arrangement and at a given distance apart as below described.

45 B, B¹ are men having enlarged bodies *b* and from which project pins *b*¹ of proper size to fit into the holes *a*¹. C, C¹ are posts having bodies *c* and pins *c*¹ also of proper size to fit into the holes *a*¹. These units are 50 characterized in some way to distinguish them from the men, for example, by being differently colored or, as shown in the drawings, by being taller and in the game of hockey are intended to be used as goal posts, as shown in the drawings, or a number of them may be used as croquet wick-

ets. Other means of causing the men to be held in stationary position on the board than that shown may be employed.

The part which I term for convenience 60 a "puck" is a thin round disk D. Any number of these may be used according to the rules of the game to be played. The stick may be made as shown of twisted wire having a handle *e* and a foot *e*¹ by which the 65 puck is struck.

In practice I prefer to make the holes *a*¹ sufficiently far apart so that when two adjacent holes are filled with men or posts or one of each the puck may be moved between 70 them.

The men B differ from the men B¹ only in having some distinguishing mark, either of color or, as shown, by identifying marks on their top so as to distinguish the men 75 on one side from those on the other.

The rules by which these game implements may be used may be made and varied at pleasure.

As shown, the board is set for beginning 80 a game of hockey, C, C being the goal posts at one end of the board between which the puck must be propelled to win the game, C¹, C¹ being the goal posts at the other end. In like manner men B, B are arranged at 85 one end of the board to guard the goal posts C¹, C¹, the puck D being placed in the middle of the board.

The game of hockey may, for example, be 90 played as follows: The player having the men B and goal C, C on winning the toss, moves a man into what seems to him a favorable position near the goal C¹, C¹. The other player moves one of his men into position anywhere on the field or board where 95 he thinks the chances of his getting the puck will be good. The first player hits the puck D with the foot *e*¹ of the stick to a point near the man he has moved. If the puck stops nearer his man than to one of his 100 opponent's he can then move another of his men up near his opponent's goal. His opponent then moves one of his men into advantageous position to block, if possible, the passage of the puck between his goal posts. 105 The first player then plays the puck again, and the game goes on as above until the puck played by the first player stops nearer one of his opponent's men than his own, when his opponent has a right to move one of his 110 men first, after which the first player moves one of his men. The opponent then strikes

the puck toward the first player's goal at the other end of the board, and the play proceeds as before. Each player will endeavor to propel the puck between the goal posts of his opponent and the right to play and first move of men after each play changes from one side to the other or not according to the position in which the puck stops after a play. The possession of the puck is with him whose man it stops nearest.

The above suggests a game which is interesting and requires considerable skill. Other games may be played upon the board, the number of pieces and their marking depending upon the game to be played. For example, a number of pieces C, C¹ may be set up in the positions of croquet stakes and wickets and a number of differently colored disks D may be used to represent balls, each player being provided with a stick by which to propel the balls. Moreover, the board may be made of a different shape from that shown.

My invention does not depend upon the number of units employed but upon a board with units of the kind described, the number of which will depend upon the game to be played.

What I claim as my invention is:—

1. A game apparatus comprising a board provided with holes scattered throughout the surface or field thereof and properly spaced apart, a plurality of posts fitted to be removably held in said holes and adapted to serve as goals or wickets, two distinguishable sets of men also fitted to be removably held in said holes so that they may be placed to occupy any desired positions on the field of said board, and one or more disks adapted to be propelled over the board, said disks being of such size that they may pass between the men or posts fitted in said spaced-apart holes.

2. A game apparatus comprising a board provided with holes scattered throughout the surface or field thereof and properly spaced apart, a plurality of posts fitted to be removably held in said holes and adapted to serve as goals or wickets, two distinguishable sets of men also fitted to be removably held in said holes so that they may be placed to occupy any desired positions on the field of said board, one or more disks adapted to be propelled over the board, said disks being of such size that they may pass between the men or posts fitted in said spaced-apart holes.

3. A game apparatus comprising a board provided with holes scattered throughout the surface or field thereof and properly spaced apart, a plurality of posts fitted to be removably held in said holes and adapted to serve as goals or wickets, two distinguishable sets of men also fitted to be removably held in said holes so that they may be placed to occupy any desired positions on the field of said board, one or more disks adapted to be propelled over the board, said disks being of such size that they may pass between the men or posts fitted in said spaced-apart holes, and an instrument for propelling said disk or disks over the field of said board.

3. A game apparatus comprising a board provided with holes scattered throughout the surface or field thereof and properly spaced apart, a plurality of posts fitted to be removably held in said holes and adapted to serve as goals or wickets, and two distinguishable sets of men also fitted to be removably held in said holes so that they may be placed to occupy any desired positions on the field of said board.

WILLIAM H. CLAUSEN.
